(57) **CLAIM**

The ornamental design for a protective folio for an input device, as shown and described.

DESCRIPTION

FIG. 1 is a perspective view of our protective folio for an input device showing our new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof;

FIG. 7 is a left side elevational view thereof;

FIG. 8 is a top plan view in a closed configuration; and,

FIG. 9 is a bottom plan view in a closed configuration.

The broken lines shown in the drawings are included for the purpose of illustrating portions of the structure that form no part of the claimed design.

1 Claim, 7 Drawing Sheets
